CLAIM

The ornamental design for a bracelet clasp, as shown and described.

DESCRIPTION

FIG. 1 is a front view of a bracelet clasp showing my new design;

FIG. 2 is a rear view of the bracelet clasp;

FIG. 3 is a left side view of the bracelet clasp;

FIG. 4 is a right side view of the bracelet clasp;

FIG. 5 is a top view of the bracelet clasp;

FIG. 6 is a bottom view of the bracelet clasp;

FIG. 7 is a top front side perspective view of the bracelet clasp; and,

FIG. 8 is a top front side perspective view of the bracelet clasp in use.

The teeth portions of the bracelet clasp in Figures 1, 3, 4, 7, and 8 shown in broken lines form no part of the claimed design. The broken line in FIGS. 1, 3, 4, 6, 7, and 8 showing surface indicia forms no part of the claimed design. The broken lines in FIG. 8 showing a bracelet are illustrative of environmental structure forming no part of the claimed design.
